SELF-CLOSING GAUGING HATCH

René Berg, New York, N. Y.

Application June 29, 1945, Serial No. 602,376

3 Claims. (Cl. 220—33)

1

This invention relates to closure assemblies, and more particularly to hatches and manholes for providing access to tanks and other containers that are used to confine liquids, for example, such as petroleum and various of the refined or partially refined products thereof.

In closures of this type it is desirable for many purposes that the cover member be supported for movement into and out of closing position without disconnection of the cover from its support. To this end such covers have been pivotally supported on a shaft or stud extending at right angles to the seating surface and swung about the support away from closed position when access to the hatch or manhole opening has been desired.

In the use and operation of such swinging covers frequently it is difficult to start the cover from its seating position, especially after having been long in contact therewith. This condition may be caused either by the adhesive character of portions of the material confined in the container with which the closure is used and which have spilled onto the seating surface, or by rusting or other corrosion of the contacting surfaces of the cover and the seat provided about the opening, or it may be caused by the formation of ice about the cover edge when the tank or other container is exposed to the weather, or for other reasons.

When closures of this type are mounted for movement in a horizontal plane about a fixed pivot, as for example, when they are used with gauging hatches and manholes associated with the roof structure of an oil tank, a tank car or other liquid receptacle, it also sometimes happens that a gauger or other operator of the closure, after he has opened it to take measurements or for other purposes, will overlook closing it, thus giving rise to avoidable losses through evaporation or undesired entry of water, dust or other contaminating substances. The operator is also frequently burdened with sampling devices, gauges or other equipment, and may be obliged to make his inspections under unsatisfactory weather conditions, all of which are contributing factors making it more likely that he may overlook closing the hatch or adding to his difficulties in performing the manipulative operations involved.

The present invention has for an object to provide an improved closure assembly of the type above indicated which enables the gauger or other person operating the closure to break the seat-

2

ing contact of the cover with the seating surface and to swing the cover away from the opening by one continued manipulation of an operating lever which may be actuated either by the hand or the foot.

It is a further object of the invention to provide for self-closing of the cover upon release of the operating lever as, for example, when the operator removes his foot from the operating lever or pedal upon completion of his inspection or measuring operations.

One of the features of the invention resides in the association with a hatch cover or the like that is mounted both for swinging movement about a supporting stud and for movement lengthwise thereof, of a lever operated cam arranged to be brought into bearing engagement with a cooperating bearing surface of the cover or an extension thereof and which when rotated in one direction will cause the cover to move axially along its supporting stud away from its supporting surface, and upon rotation in the opposite direction, permits the return sliding movement of the cover axially of the supporting stud toward its seating position.

Another feature of the invention resides in the provision of a turning sector mounted for rotation by the cam operating lever and operable, after an appropriate interval of movement of the cam sufficient to insure unseating of the cover member, to impart swinging movement of the cover member about its supporting stud through suitable connections with the cover.

A still further feature of the invention resides in the provision of an extension of the cam which acts as a dwell furnishing a low friction bearing support for the cover and maintaining it in the predetermined raised position during the swinging movement of the cover.

Still another feature of the invention resides in the provision of an adjustably counterweighted lever arm disposed in counter-balanced relation to the operating lever or pedal and acting through suitable connections with the turning sector to bias the cover to its normally closed or seating position when the operating lever is released.

The invention includes as a further feature an improved arrangement of means for forcing the cover into pressure sealing engagement with the seating surface of the hatch and to maintain it under any desired degree of pressure during intervals between operations of the closure.

Other objects and features of the invention

will appear from the following description taken in connection with the drawings in which:

Fig. 1 is a plan view of a closure assembly embodying the invention with the cover in closed position;

Fig. 2 is a part vertical section and part side elevations, with section taken on line 2—2 of Fig. 1;

Fig. 3 is a side elevation taken at the left hand side of Figs. 1 and 2;

Fig. 4 is a vertical section on line 4—4 of Fig. 2 with the cam rotated into position to raise the cover from the seating surface;

Fig. 5 is a fragmentary plan view showing the cover in position to expose the opening normally closed thereby; and

Fig. 6 is a section on line 6—6 of Fig. 2.

In the embodiment of the invention as shown in Figs. 1 and 2, the closure assembly comprises the ring flange 1 extending about the opening 2. The flange may be bolted as at 3 to the roof or other supporting wall portion of the tank or other container with which the closure is associated. The flange 1 is provided with an upstanding annular shoulder 5, Fig. 2, terminating in a planar face 9. A groove 7 is formed in the face 9 and receives a gasket 11 providing a seating surface 12 upon which bears the planar face 13 at the under side of the cover 14. The cover 14 is pivotally supported upon the stud 16 having its end portion 17 threaded into a threaded hole in the flange 1. The stud 16 is formed with a shoulder 18 bearing on the upper surface of the flange 1 and is provided with an hexagonal bolt head 19 to receive a wrench for screwing the stud fast in the threaded hole in the flange 1 and for other purposes hereafter described. The cover 14 is provided with a hub portion 21 having a bore fitting to the stud 16 to provide for the pivotal or swinging movement of the cover about the axis of the stud 16 in a plane parallel to the seating surface 12 of the gasket 11. The hub 21 is also so fitted to the stud 16 as to provide for sliding movement of the hub along the stud 16 when carrying the cover 14 vertically upward or downward from or to the seating surface 12.

The hub 21 of the cover 14 also is provided with a laterally extending portion 23 having on its under side 24 a cam follower surface for engagement by the cam 25. As hereinafter more fully described when rotated in one direction the cam 25 exerts upward pressure upon the hub 21 to slide it upwardly along the stud 16, thereby lifting the cover from the seating surface 12. The cam is so formed that it operates to lift the cover from the seating surface 12 prior to operation of the mechanism to be described for effecting the swinging movement of the cover 14 to a position uncovering the hatch opening 2.

As may be seen in Fig. 3, the cam surface 26 of cam 25 is so formed as to permit the cover 14 to seat upon the surface 12 when the lever 28 is in a lifted position as shown in Fig. 3. As shown the cam 25 is formed integrally with the hub of the lever 28 and, therefore, is rotatable therewith about the axis of the supporting stud 30. When the lever 28 and cam 25 are rotated counterclockwise as shown in Fig. 3, about the axis of the stud 30 the dwell portion 27 of the cam 25, which is in the form of a circular arc, will eventually be brought into engagement with the cam follower surface 24. So long as the surface 24 is in engagement with the dwell 27, the cover will be maintained in its lifted posi-

tion and is free for swinging movement about the stud 16. Since the follower surface establishes a line contact with the dwell 27, the resulting bearing offers little frictional resistance to turning movements of the cover. Upon reverse movement of the lever 28, the arcuate dwell surface 27 is moved along the cam follower surface 24 until the toe of the cam surface 26 engages said surface 24. Thereafter upon further reverse movement of the lever 28 and cam 25, the hub 21 and the cover 14 may slidably move under their weight downwardly along the stud 16 until the seating surface 13 of the cover comes into contact with the seating surface 12 of the gasket 11.

In the embodiment of the invention as shown in Figs. 1, 2 and 3, the stud 30 is supported by brackets 35 and 36 formed upon an extension 34 of the flange 1. The stud 30 may be provided with a head 31 and may be held in place by a set screw 37 in the bracket 35.

Also pivotally supported by stud 30, as shown in Figs. 3 and 4, and so as to move thereon in oscillating movement independently of the cam 26 for part of its camming rotation, is a member 40 in the form of a sector connected to a hub 21 the bore of which rotatably fits upon the stud 30. At the peripheral arcuate portion of the sector 40 and extending laterally from the web 42 thereof is a lug 44 formed and arranged to engage an upstanding projection or pin 46 carried by the extension 23 of the hub 21. In Fig. 3 the lug 44 is shown in engagement with the pin 46 so that movement of the sector 40 in a counterclockwise direction will cause the hub 21 and the cover 14 integral therewith to rotate clockwise as viewed in Fig. 1, about stud 16. The proportions of the parts and their relation are such that the pin 46, the hub 21 and the cover 14 move through an angle of approximately 90° in the embodiment illustrated, from the closed position as shown in Fig. 1 to a position substantially 90° therefrom as shown in Fig. 5, when the sector 40 is rotated to the full extent possible when actuated by the lever 28.

In order to effect such movement of the sector 40 and of pin 46 to produce opening movement of the cover, the cam 25 is provided with a laterally extending lug 50 for engagement with the edge surface 43 of said sector 40. As will be seen from Fig. 3, when the lever 28 is in fully raised position, the cover 14 being in closed position in contact with seating surface 12 and the lug 44 being in engagement with the pin 46, the lug 50 is spaced from the edge surface 43 of the sector 40. Movement of the lug from the position shown in Fig. 3 to a position in which the lug 50 is in contact with the edge surface 43, as shown in Fig. 4, occurs concomitantly with movement of the lever 28 from the position shown in Fig. 3 downwardly through the distance required for the cam surface 26, acting on the cam follower surface 24, to lift the cover from the seating surface 12. During movement of the lug 50 into contact with the edge 43 of the sector 40 there is thus provided a lost motion between these parts which prevents movement of the sector during the cover lifting movement of the cam. Upon further movement of the lever 28 downwardly from the position shown in Fig. 4 the lug 50 bearing on the surface 43 moves the sector 40, counterclockwise in Fig. 3 and clockwise in Fig. 4, about the stud 30 to open the closure as above described.

The sector 40 is provided with a weight arm 60 extending outwardly therefrom to carry an ad-

justable counterweight 62. When hand or foot pressure is withdrawn from the lever 28, the counterweight 62 and weight arm 60 are effective to bias the sector 40 to movement clockwise in Fig. 3, counterclockwise in Fig. 4, about the stud 30, thereby effecting reverse movement of the cam 25 and, as a part of the same biasing movement of sector 40, producing return movement of the cover 14 to its position covering the opening 2. For this latter purpose the sector 40 is provided with a laterally extending lug 66 for engagement with the upstanding pin 46 at the opposite side thereof from the lug 44. The lug 66 like the lug 44, in consideration of the proportions of the parts, is capable of effecting movement of the pin 46, and, therefore, of the cover 14 reversely through the angle of 90° through which they have been moved in clockwise direction by the lug 44 acting on the pin 46. This closing movement may take place during the time in which the arcuate surface 27 of cam 25 is in contact with the cam follower surface 24, thus holding the cover up from the seating surface 12 during this reverse movement. When the cover reaches its registering position above the opening 2, the lug 50 reaches the position shown in Fig. 4 still in contact with but about to leave the edge surface 43 of the sector 40. Under its weight the cover 14 then moves downwardly until it comes in contact with the seating surface 12, the cam follower surface 24 bearing on the cam toe to move the cam to the position shown in Fig. 3, thus moving the lug 50 away from the edge surface 43 and further raising lever 28 to the position of Fig. 3.

In order to prevent swinging movement of the cover beyond its registering position with respect to the opening 2 and also to provide means for pressing the cover disk 14 on to the seat 12, a yoke 70 is provided and arranged for swinging movement with the cover to and from closing position. As shown, the yoke 70 is provided with a hub 72, the bore of which fits on the stud 16 to permit the yoke 70 to pivot about the stud 16 in a plane parallel to the plane of the swinging movement of the cover 14 and also to move slidably along stud 16. The opposite end of the yoke 70 is provided with a forked hub 74 for engagement with the stud 78 threaded at its lower end 79 into and provided with shoulder 80 bearing on the upper surface of the flange 1. The stud 78 is provided with an hexagonal bolt head 81. The upper surfaces of the hubs 72 and 74 respectively may bear against the heads 19 and 81 of the studs 16 and 78 when the yoke 70 is forced upwardly thereagainst. The yoke 70 is provided with a stiffening web 83.

In order that the yoke 70 may have a swinging movement corresponding with that of the cover 14, a suitable connection is established between the cover and the yoke. As shown the connection includes an upwardly extending bracket 85 carried on the cover 14 and having a lug 87 extending upwardly therefrom. Extending downwardly from the yoke 70 at either side of the lug 87 are ears 89, one or the other of which is engaged by the lug 87 when the cover 14 is swung upon the stud 16 to or from closing position with respect to the opening 2, thereby carrying the yoke 70 with the cover in its swinging movement. By means about to be described, force may be exerted between the cover 14 and the yoke 70 to force these two members apart. It will be apparent from consideration of Fig. 2 that when the hubs 72 and 74 are in contact with the bolt heads 19 and 81, force so applied will act to press the cover

14 downwardly upon the seating surface 12. Upon release of such force the yoke may move slidably downward along the studs 16 and 78 until the lower face of the yoke 70 rests upon the top surface 88 of the lug 87.

In order to prevent binding of the yoke 70 on the stud 16 due to tilting, a tap bolt 110, Fig. 3, having a head 111 is threaded in the side of stud 16. Upon said bolt 110 a roller 112 is rotatably supported so that the under surface of the hub 72 may rest thereon when the bottom face of the yoke 70 rests on the upper surface 88 of the lug 87 attached to the bracket 85 when the yoke is released as above mentioned. As the yoke is carried in swinging movement with the cover 14, the yoke may move on said roller 112. The location of the tap bolt 110 vertically along the stud 16 is such that the lower face of the hub 72 may be in contact with the roller 112 when the cover 14 is in the position to which it is lifted by the operation of the cam 25.

In order to produce the force necessary initially to move the yoke 70 upwardly into contact with the bolt heads 19 and 81 and thereafter to press the cover 14 downwardly upon the seating surface 12, the cover 14 is provided with an additional bracket 91 extending upwardly therefrom and spaced from bracket 85. Through suitable holes in brackets 85 and 91 a pin 93 passes to provide a pivot for a cam lock. The stud 93 is provided with a head 94 bearing on the outer face of the bracket 91 and is held in place by a cotter pin 95 in contact with the outer face of the bracket 85. Pivotally mounted upon the pin 93 is a cam 97, the outline of which is shown in Fig. 6, having a cam surface 99 formed for contact with the under surface of the yoke 70. The cam 97 is provided with a pair of lever arms 101 and 102 in such angular relation to each other and to the cam surface 99 that when the arm 101 is pressed downwardly, the cam lifts the yoke 70 with respect to the cover 14. When the arm 102 is pressed downwardly, thus raising the arm 101, the cam surface 99 moving with respect to the under surface of the yoke 70 permits this yoke to drop until it is in contact with the lug 87 and with roller 112. Thereafter, further downward movement of the arm 102 releases the pressure of the cam from the yoke and leaves the cover in unlocked condition, that is, without pressure being exerted thereon tending to separate the yoke and the cover. When the cover is in unlocked condition, the end 32 of the lever 28 may be depressed to lift the hub 21 and break the seating contact of the cover 14 with the seating surface 12. Thereafter, as above described, the swinging movement of the cover may take place upon further depression of the lever 28. It will be apparent that when the lever 102 is in the downwardly pressed position, the cam thus effecting "locking" of the cover, lifting of the cover from its seat by operation of the lever 28 is not possible. Inadvertent operation of the lever 28 by foot or otherwise thus is prevented until care has been taken to unlock the cover by operation of the cam 97 by means of the lever 102.

It will be apparent from the above description that all of the parts requisite for breaking the contact of the cover with the seating surface 12, swinging movement of the cover from its position covering the opening 2 to its position uncovering said opening, as well as for locking and unlocking the cover are compactly and conveniently ar-

ranged in the closure device of the invention so that operation thereof preferably by foot pressure may be readily accomplished. The cover may first be unlocked by pressure of the foot upon the lever 102. Thereafter depression of the lever 28 breaks the contact and continued pressure on lever 28 swings the cover to uncover the opening. In this swinging movement the parts which constitute the lock mechanism are carried with the cover and are ready in place for locking operation upon return movement of the cover to its position covering the opening. Moreover because of the provision of the counterweight 62 and the parts operatively connecting this weight to the cover, the cover is always in the position covering the opening unless held away therefrom by operation of the lever 28. Even though inadvertently the cover were not locked by operation of the cam 97 the cover normally closes the opening 2 and is held in contact with and in covering relation to the seating surface 12 by virtue of its own weight and that of the yoke 70, and by virtue of the biasing action of the counter-weighted arm 60 acting through lug 66, as above described.

It will be understood that although the closure illustrated in the drawings is shown for operation in connection with an opening having a seating surface disposed in a horizontal plane, that is, the face of the flange 1 is horizontal, the device may be used in connection with flanged opening or hatches that have a moderate degree of inclination to the horizontal. In a closure such as illustrated and embodying the self-closing feature, the inclination should not be so great that the plane of action of the counterweight 62 and of the weight arm 60 is ineffective to produce turning movement of the sector 40 upon the axis of the stud 30. In the broader aspects, however, the self-closing embodiment of the invention includes constructions in which are provided means effective first to lift the cover from the seating surface and thereafter pivotally to move said cover to a position exposing the opening and preferably in a plane generally parallel to the plane of the seating surface, together with biasing means for effecting return movement of the cover to the seating surface.

It will be understood, however, that the camming arrangement which permits of unseating or cracking of the sealing engagement of the cover with its seat and then swinging of the cover to one side all as a part of the same continued operating movement may be applied without reference to the horizontality or inclination of the hatch opening and with or without association with means for insuring self-closing or return movement of the elements involved.

Various other changes in the arrangements of the structural elements and adaptations of the features of the invention to many situations other than those mentioned herein may be made without departing from the invention, which is not to be deemed as limited otherwise than as indicated by the language of the appended claims.

I claim:

1. In a closure for hatch openings and the like, in combination, a flange providing a seat extending about said opening, a stud supported on said flange adjacent said seat, a cover adapted to be brought into engagement with said seat when in covering relation to said opening and pivotally and slidably supported on said

70
75

stud, a rotatable cam normally in engagement with a cam follower surface operatively connected to said cover and operable through said engagement to effect sliding movement of said

5. cover lengthwise of said stud to lift said cover from said seat, a projection carried by said cover to move therewith about said stud in the pivotal movement of said cover on said stud, a sector member supported for oscillating movement and having a lug for engaging said projection to produce movement of said projection about said stud to effect pivotal movement of said cover upon oscillating movement of said sector member, a lever connected to said cam to effect initially said sliding movement of said cover by said operation of said cam upon operation of said lever, said cam having a lug arranged thereon so as to engage said oscillatable sector member upon further movement of said lever 20 to produce said pivotal movement of said cover after said cam effects said sliding movement thereof.

2. In the combination according to claim 1, means operatively connected to said oscillatable 25 sector member and said lever and biased to oppose said operation thereof to effect opening movement of said cover, said oscillatable sector member having a second lug for engaging said projection carried by said cover to effect closing 30 movement of said cover under the action of said bias means.

3. In an enclosure for a hatch opening or the like, in combination, a flange providing a seat 35 extending about said opening, a stud supported on said flange adjacent said seat, a cover adapted to be brought into engagement with said seat when in covering relation to said opening and pivotally and slidably supported on said stud, a yoke slidably and pivotally movable on said stud and having means engaging said cover to effect said pivotal movement of said yoke concomitantly with the pivotal movement of said cover, camming means acting upon said yoke and said cover and operable to effect separating 45 movement of said yoke and said cover relative to each other, a second stud supported on said flange oppositely across said opening from said first stud and engaged by said yoke when said cover is in said covering relation to said opening, 50 said studs providing means for resisting movement of said yoke away from said seat, whereby said cover is pressed upon said seat upon operation of said camming means, a rotatable cam normally in engagement with a cam follower surface operatively connected to said cover and operable through said engagement to effect sliding movement of said cover lengthwise of said first stud to lift said cover from said seat, and means operatively connected to said cover and to said cam and operable, after said cam has been rotated sufficiently to unseat said cover, to pivotally move said cover from its closed position to a position clear of said opening.

RENE BERG.
